M. S. WRIGHT.
PNEUMATIC ACTION FOR MUSICAL INSTRUMENTS.
APPLICATION FILED NOV. 3, 1914.
1,312,495.

Patented Aug. 5, 1919.

UNITED STATES PATENT OFFICE.

MORRIS S. WRIGHT, OF WORCESTER, MASSACHUSETTS.

PNEUMATIC ACTION FOR MUSICAL INSTRUMENTS.

1,312,495.

Specification of Letters Patent. Patented Aug. 5, 1919.

Application filed November 3, 1914. Serial No. 870,083.

To all whom it may concern:

Be it known that I, MORRIS S. WRIGHT, a citizen of the United States, residing at Worcester, in the county of Worcester and State of Massachusetts, have invented certain new and useful Improvements in Pneumatic Actions for Musical Instruments, of which the following is a specification, reference being had therein to the accompanying drawing.

This invention relates to pneumatic actions for self-playing musical instruments.

In the art under consideration, many devices have proven largely impracticable because due consideration was not given to the objection of leakage between the pneumatic and valve parts, and the objection of the accumulation of dust on the various operative parts, and it is one of the primary objects of the present invention to provide means whereby the primary pneumatics and associated valve members may be entirely inclosed and protected from dirt and dust, and the likelihood of leakage between the parts effectively guarded against.

An additional and important advantage of inclosing the parts just mentioned, as contemplated by the present invention, resides in the fact that the usual noise incident to the breathing of the pneumatics will be avoided, thereby eliminating an objection to mechanical self-playing instruments of previous construction.

In carrying out the invention I preferably constitute the wind chest or vacuum chamber casing, as the inclosing housing for the valve and primary pneumatic parts, said inclosing housing having a movable or detachable part whereby to afford convenient access to the pneumatic and valve parts, as desired.

It is also contemplated by the present invention to so construct and arrange the primary pneumatics and valve parts within the vacuum chamber casing that the same may, if desired, be bodily detached and removed from the vacuum chamber casing through the opening normally closed by the detachable part previously referred to.

A further object of the invention is to provide a pneumatic action involving a fewer number of parts, and cheaper to produce than prior similar actions, and with these and other objects in view, it is proposed by my improvements, to dispense with the usual piping or conductors between the pneu-

matics, valve parts, and vacuum chamber casing, and to provide direct connection and communication between these parts.

In the preferred embodiment of the present invention, as illustrated, the motor pneumatic is positioned without the vacuum chamber casing, and is adapted to have direct communication with the operatively associated valve casing through an opening in one of the walls of the vacuum chamber casing.

It is further proposed by the present invention to provide means whereby the parts comprising the motor pneumatic, primary pneumatic and valve casing may be supported in place on the vacuum chamber casing by common means, to the end that by disengaging this means the several parts may be removed at one and the same time.

Still further, it is contemplated by the present invention to provide a novel and improved pneumatic action, one that will be relatively inexpensive, while, at the same time, strong and durable in use, and highly efficient in operation.

Other improvements and novel details in the construction and arrangement of the various parts will be appreciated by those skilled in the art from the description to follow, which, for a clear understanding of the invention, is to be considered in connection with the accompanying drawings, forming a part hereof, and wherein is disclosed, for the purpose of illustration, a convenient and satisfactory embodiment of the invention.

In the drawings:—

Figure 1 is a side elevation of the device with parts in section; 95

Fig. 2 is a top plan of one of the sections, the vacuum casing being in section.

Referring more particularly to the drawings, wherein like reference numerals refer to corresponding parts throughout the several views, the vacuum chamber or wind chest X, which preferably constitutes an inclosing housing for the primary pneumatics and valve members, is conveniently of metallic formation, and comprises top and bottom walls, 1 and 2, respectively, a rear wall, 3, end walls 4; the rear and end walls being preferably integral with the top and bottom walls, and removable front wall 5.

The front wall 5 is preferably of a size to overlie the edges of the top and bottom and end walls of the casing, and said top,

bottom and end walls preferably have an outwardly extending flange 6, to be engaged by the edges of the removable front wall 5. Removable securing means for the front wall 5 is preferably provided by threaded bolts 7, projecting from the edge extensions of the front wall and passing through suitable apertures in the flanges 6 of the coöperating walls of the vacuum chamber casing.

10 It is also desirable to provide a packing, as of felt, 8, between the flanges 6 and the front wall, whereby to effectively seal the joint, to the end that the vacuum chamber casing will be air tight throughout.

15 Positioned within the housing formed by the vacuum chamber casing are a series of pneumatic and valve actions, and a description of one of these parts will suffice for the others, it being understood that, as is usual 20 in this type of construction, these pneumatics and valve units are arranged in a plurality of vertically spaced horizontal series, the units of succeeding series being out of vertical alinement.

25 The combined primary pneumatic and valve casing is preferably of metallic formation, and of the following construction.

9 is a bottom wall for the primary pneumatic casing, and 10 a top wall therefor, 30 the bottom wall being provided with a peripheral supporting flange 11, for a peripheral flange at the lower edge of the top wall, and said supporting flange of the bottom wall conveniently has a plurality of 35 bendable lips 12, adapted to be bent over the upper surface of the peripheral flange at the lower edge of the top wall whereby to detachably connect these parts together.

40 Interposed between the flanges of the top and bottom walls of the primary pneumatic casing is a suitable flexible diaphragm or pneumatic proper 13. The top wall 10 of the primary pneumatic casing is provided with a horizontal part 14, an upwardly extending part 15, and an auxiliary horizontally extending part 16, which latter terminates with a downwardly projecting annular flange 17, the flange 17 forming a suitable 45 guide way for the valve, to be presently described, and the various portions of the top wall of the primary pneumatic casing just referred to, coöperate to form a bottom wall for the valve casing.

The valve casing conveniently comprises 50 a vertically extending tubular wall 18, having a relatively flat open side portion 19 to engage the inner surface of the rear wall 3 of the vacuum chamber casing.

A removable top 20 is provided for the 60 upper end of the tubular valve casing, a suitable packing 21 being provided between the top 20 and the upper edge of the tubular valve casing, whereby to form a sealed closure for the valve casing.

65 A suitable partition 22 having a central

opening 22^a provides at its lower surface a valve seat, said partition being extended to the relatively flat side wall 19, and said side wall being provided with an opening 23 to form an outlet for the chamber above the 70 partition.

A yieldable packing 24 is interposed between the lower edge of the vertical tubular portion of the valve casing and the horizontally extending flange 14 of the primary 75 pneumatic top, whereby to form an effective seal between these parts, and a suitable yieldable washer 16^a is provided upon the horizontally extending part 16, of the top wall of the primary pneumatic casing, to 80 coöperate with said horizontally extending wall in providing a valve seat.

Positioned upon the flexible diaphragm or pneumatic 13 in any appropriate manner, whereby to receive movement therefrom, is 85 a suitable valve stem 25, having positioned thereon, a suitable valve disk 26, of any desired construction, the said disk being adapted to engage the washer 16^a. Said valve stem also preferably has a series of 90 laterally extending wings 25^a, whereby to properly center the same in its movement through the opening in the top wall of the primary pneumatic. The valve stem 25 has an extensible part 27, threaded thereto, 95 which said part 27 terminates in a flattened head 28, adapted to provide a loose support for a valve cap 29, the said cap being adapted to support a valve disk 30, having a yieldable surface adapted, in the upward 100 movement of the valve stem to engage the valve seat provided by the partition 22. The valve cap 29 is conveniently shaped somewhat similar to the flattened end of the valve stem part 27 to the end that by imparting rotary movement to the cap 29, the stem is rotated, whereby to relatively adjust the valve parts. At the same time, the valve, by reason of the loose connection 105 stated, may readily rock and be properly 110 centered in action.

Access may be afforded for adjustment of the valve parts by removing the detachable top 20 of the valve casing. The top wall 10 of the primary pneumatic is provided with 115 a series of openings 31, whereby to establish direct communication between the pneumatic casing and the vacuum chamber, at a point above the diaphragm and at a point below the lower valve disk.

120 Communication between the primary pneumatic casing and the tracker bar, which latter may be of any approved design, is preferably provided through the medium of a tubular coupling member 32 secured to the 125 bottom wall 9 of the primary pneumatic, and projecting downwardly and upwardly therefrom. A conduit or conductor 33 projects upwardly at the front of the primary pneumatic casing and has at its lower end 130

an angled extension 34 adapted to be detachably connected to the coupling member 32, preferably through the medium of a tubular rubber member 35, and a surrounding tubular metallic member, the surrounding tubular metallic member having indentations whereby to force the tubular rubber member, which overlies the adjacent ends of the conductor parts, into air tight contact with 10 said parts.

The conductor part 33 at its upper end preferably connects with a curved part 36, projecting inwardly through the rear wall 3 of the vacuum chamber casing, for connection with the tracker bar, and if desired, this connection may be afforded by detachable tubular units coupled one to the other in the manner previously described with reference to the connection between the coupling 22 and the member 33.

It is understood, of course, that the member 36 is also connected to the member 33 by a similar detachable coupling to the end that these various sections may be detached, 25 as desired. That portion 36 of the conductor is conveniently provided with a vent opening 37, communicating with the vacuum chamber.

The motor pneumatic is preferably positioned without the vacuum chamber casing, and comprises an upper stationary wall 38, an end wall 39, and a movable bottom wall 40, the said walls being connected one to the other by flexible folds 41. The lower movable wall of the pneumatic has a suitable bracket 42, adapted for connection with a rod 43, of any desired construction, designed to actuate the striking means proper. The power pneumatic is preferably secured at its 40 end, 39, to the wall 3 of the vacuum chamber casing, at a point adjacent the valve casing, previously described, whereby direct communication between the power pneumatic and the valve chamber casing is provided by an opening 44, in the wall 3 of the vacuum chamber casing, adapted to register with openings 45 and 46 in the wall of the valve chamber casing and the end wall of the power pneumatic, respectively.

50 A suitable packing 47 is provided between the valve casing and the wall 3 of the vacuum chamber casing, and between the outer surface of said wall 3 and the end wall of the power pneumatic.

55 In the preferred embodiment of the invention I conveniently provide a single means for securing the motor pneumatic, primary pneumatic casing, and valve casing to the wall of the vacuum chamber casing, the said means including a metallic band or strap 48, overlying the wall of the valve casing, and having offset feet 49, to engage the inner surface of the wall 3 of the vacuum chamber casing. Removable threaded 60 bolts 50 project through openings in the

offset feet 49, rear wall 3, and engage the end wall of the vacuum chamber casing. If desired, anchoring dowels, as of brass 51, may be embedded in the end wall of the motor pneumatic to be engaged by the terminals of the bolts 50, whereby to firmly support these parts in place.

70 The operation may be reviewed as follows:

The primary pneumatic elements being 75 provided with the holes 31 in the top wall thereof, allows the vacuum in the chamber X to connect with the valve chamber, so that when the air is admitted to the conductor connected to the tracker, the same 80 follows under the diaphragm 13, lifts the valve 26, closing the opening 22 by means of the valve disk 29, so that the atmospheric pressure is cut off from the power pneumatic. As the air is cut off from the 85 tracker, the power pneumatic takes the remaining air from the opening 44 in the wall 3 leading to the outside.

When it is desired to obtain access to any of the parts, it is only necessary to remove 90 the detachable front wall 5 of the casing. Should it be desired to remove the pneumatic elements from the casing, the conductor section 33 is removed from the section 36, and the bolts 50 released, which 95 will disconnect the valve casing and connected pneumatics to the end that the same may be bodily removed from the vacuum chamber casing.

100 It will be seen from the description that the primary pneumatics and valve mechanism are all inclosed and protected from dirt and dust, and it will also be appreciated that the structure is simple and inexpensive in that the customary conduits between the 105 parts, the usual vent bar, etc., are eliminated.

In addition to the advantage of protecting the parts from the accumulation of dirt and dust, the inclosing characteristic is important in that the noise incident to 110 the breathing of the pneumatic will be largely eliminated.

I claim:

1. In a pneumatic action for musical instruments, the combination of a vacuum 115 chamber casing, a series of primary pneumatic elements and valve casings arranged wholly within the vacuum chamber casing, valves within the valve casings and inclosed thereby and power pneumatics one for each 120 valve casing arranged without the vacuum chamber casing and operatively associated with the valve casings.

2. In a pneumatic action for musical instruments, the combination of a metallic 125 vacuum chamber casing, a series of primary pneumatic and valve casings, the walls of which are constructed of metal and arranged wholly within the vacuum chamber casing, and power pneumatics one for each valve 130

casing arranged without the vacuum chamber casing and operatively associated with the valve casings, and a detachable wall for the vacuum chamber casing, permitting access to the primary pneumatics and valve casings.

3. In a pneumatic action for musical instruments, the combination of a vacuum chamber casing, a valve casing positioned 10 within the vacuum chamber casing, a primary pneumatic operatively associated with the valve casing, a motor pneumatic arranged without the vacuum chamber casing, means for establishing direct communication 15 between the valve casing and the motor pneumatic through one wall of the vacuum chamber casing, and means for detachably supporting the motor pneumatic and valve casing on said wall of the vacuum 20 chamber casing.

4. In a pneumatic action for musical instruments, the combination of a vacuum chamber casing, a valve casing positioned within the vacuum chamber casing, a primary pneumatic operatively associated with the valve casing, a motor pneumatic arranged without the vacuum chamber casing, means for establishing communication between the valve casing and the motor pneumatic, and means common to the motor pneumatic and valve casing for detachably supporting both on one wall of the vacuum 30 chamber casing.

5. In an pneumatic action for musical instruments, the combination of a vacuum chamber casing, a valve casing positioned within the vacuum chamber casing, a primary pneumatic operatively associated with the valve casing, a motor pneumatic arranged without the vacuum chamber casing, one wall of the vacuum chamber casing having an opening therethrough, and the valve 40 casing and motor pneumatic having registering ports adapted to establish communication 45 with one another through said opening of the vacuum chamber casing.

6. In a pneumatic action for musical instruments, the combination of a vacuum chamber casing, a valve casing positioned 50 within the vacuum chamber casing, a primary pneumatic operatively associated with the valve casing, a motor pneumatic arranged without the vacuum chamber casing, one wall of the vacuum chamber casing having an opening therethrough, and the valve 55 casing and motor pneumatic having ports adapted to establish communication with one another through said opening of the valve casing, and means for detachably connecting 60 the motor pneumatic and valve casing upon opposite sides of the opening in said wall.

7. In a pneumatic action for musical instruments, the combination of a vacuum chamber casing, a valve casing positioned 65 within the vacuum chamber casing, a pri-

mary pneumatic operatively associated with the valve casing, a motor pneumatic arranged without the vacuum chamber casing, means for establishing communication between the valve casing and the motor pneumatic, means for detachably supporting the motor pneumatic and valve casing on the vacuum chamber casing, and a removable closure for the vacuum chamber casing permitting access to the primary pneumatic and valve casing.

8. In a pneumatic action for musical instruments, the combination of a supporting wall, a valve casing, a motor pneumatic, said supporting wall having an opening therethrough, and said motor pneumatic and valve casing having an opening in one wall thereof, and means for supporting the valve casing and motor pneumatic upon opposite sides of said supporting wall whereby the 85 openings thereof directly register with the opening in the supporting wall:

9. In a pneumatic action for musical instruments, the combination of a supporting wall, a valve casing, a motor pneumatic, 90 said supporting wall having an opening therethrough, and said motor pneumatic and valve casing having an opening in one wall thereof, and means for supporting the valve casing and motor pneumatic upon opposite 95 sides of said supporting wall whereby the openings thereof register with the opening in the supporting wall, said means including a member mounted on the valve casing and having associated means to engage the motor 100 pneumatic through said supporting wall.

10. In a pneumatic action for musical instruments, the combination of a supporting wall, a valve casing, a motor pneumatic, said supporting wall having an opening therethrough, and said motor pneumatic and valve casing having an opening in one wall thereof, and means for supporting the valve casing and motor pneumatic upon opposite sides of said supporting wall whereby the 110 openings thereof register with the opening in the supporting wall, said means including a detachable element or elements projecting through said supporting wall and operatively connected at opposite ends to 115 the valve casing and motor pneumatic.

11. In a pneumatic action for musical instruments, the combination of an inclosing vacuum chamber casing, one portion thereof forming a supporting wall, a valve casing, a 120 motor pneumatic, said supporting wall having an opening therethrough, and said motor pneumatic and valve casing having an opening in one wall thereof, and means for supporting the valve casing and motor pneumatic upon opposite sides of said supporting wall whereby the openings thereof register with the opening of the supporting wall.

12. In a pneumatic action for musical instruments, the combination of a vacuum 130

- chamber casing, a primary pneumatic and valve casing positioned within the vacuum chamber casing, a motor pneumatic arranged without the vacuum chamber casing, the valve casing and motor pneumatic having an opening therethrough and one wall of the vacuum chamber casing having an opening in registration with the openings of the valve casing and motor pneumatic, means for detachably securing the valve casing and motor pneumatic in place, and a packing interposed between the adjacent walls of the vacuum chamber casing, the motor pneumatic and valve casing.
13. In a pneumatic action for musical instruments, the combination of a primary pneumatic casing, valves, a valve casing inclosing said valves and mounted upon the primary pneumatic casing, and an inclosing casing for the primary pneumatic casing and valve casing, said inclosing casing forming a vacuum chamber.
14. In a pneumatic action for musical instruments, the combination of a primary pneumatic element, a valve casing mounted thereon, an inclosing vacuum chamber casing for the primary pneumatic element and common valve casing, and means engaging one wall of the inclosing casing for detachably supporting both the primary pneumatic element and valve casing in place.
15. In a pneumatic action for musical instruments, the combination of a primary pneumatic casing, a valve casing mounted thereon, an inclosing casing independent of the main casing of the instrument for the primary pneumatic and valve casings, and means engaging one wall of the inclosing casing for detachably supporting both the primary pneumatic and valve casings in place, and a movable closure for the inclosing casing permitting access to said detachable parts.
16. In a pneumatic action for musical instruments, the combination of a primary pneumatic, a valve casing mounted upon a part connected with said pneumatic, an inclosing vacuum chamber casing for the primary pneumatic and valve casing, means engaging one wall of the vacuum chamber casing for detachably supporting the primary pneumatic and valve casing in place, and a motor pneumatic supported on the vacuum chamber casing and operatively associated with said valve casing.
17. In a pneumatic action for musical instruments, the combination of a primary pneumatic casing, a valve casing mounted thereon, an inclosing vacuum chamber casing for the primary pneumatic and valve casings, means engaging one wall of the vacuum chamber casing for detachably supporting both the primary pneumatic and valve casings in place, and a motor pneumatic supported on the vacuum chamber casing and
- operatively associated with said valve casing, said motor pneumatic being in direct communication with the valve casing through an opening in one wall of the latter.
18. In a pneumatic action for musical instruments, the combination of a primary pneumatic, a valve casing operatively connected therewith, a vacuum chamber casing, the said primary pneumatic and valve casing being positioned within and inclosed by the vacuum chamber casing, and a motor pneumatic positioned without the vacuum chamber casing mounted upon one wall thereof and in communication with the vacuum chamber.
19. In a pneumatic action for musical instruments, the combination of a primary pneumatic element, a valve casing, secured thereto, a vacuum chamber casing, the said primary pneumatic element and valve casing being positioned within and inclosed by the vacuum chamber casing, said vacuum chamber casing having an opening leading to the outside and communicating with the valve casing.
20. In a pneumatic action for musical instruments, the combination of a primary pneumatic casing, a valve casing connected directly thereto, a vacuum chamber casing, the said primary pneumatic and valve casings being positioned within and inclosed by the vacuum chamber casing, and a conduit within the casing communicating with the primary pneumatic casing and leading to the outside of the casing for connection with a tracker bar.
21. In a pneumatic action for musical instruments, the combination of a primary pneumatic, a valve casing connected thereto, a vacuum chamber casing, the said primary pneumatic and valve casing being positioned within and inclosed by the vacuum chamber casing, and a conduit within the casing communicating with the primary pneumatic and leading to the outside of the casing for connecting with a tracker bar, said conduit being formed in sections, whereby to permit removal of the valve casing and primary pneumatic.
22. In a pneumatic action for musical instruments, the combination of a primary pneumatic casing, a valve casing mounted thereon, a vacuum chamber casing, the said primary pneumatic and valve casings being positioned within and inclosed by the vacuum chamber casing, and a conduit within the casing communicating with the primary pneumatic casing and leading to the outside of the casing for connection with a tracker bar, said conduit having a vent opening within the vacuum chamber.
23. In a metallic pneumatic action for musical instruments, the combination of a metallic casing forming a vacuum chamber, and a metallic unit within the chamber com-

prising a primary pneumatic and valve casing.

24. In a metallic pneumatic action for musical instruments, the combination of a metallic casing forming a vacuum chamber, a metallic unit within the chamber comprising a primary pneumatic and valve casing, means for detachably securing said unit in place, and a removable wall for the vacuum chamber casing.

25. In a pneumatic action for musical instruments, the combination of a vacuum chamber casing, a primary pneumatic element positioned within the casing, having opposite walls with an interposed diaphragm, a conduit adapted for connection with the tracker bar, communicating with the lower wall of the primary pneumatic, and the opposite wall having a port communicating with the vacuum chamber, and a valve casing supported upon the primary pneumatic element, and also inclosed by the vacuum chamber casing.

26. In a pneumatic action for musical instruments, the combination of a vacuum chamber casing, a primary pneumatic casing positioned within the casing, having opposite walls with an interposed diaphragm, a conduit adapted for connection with the tracker bar, communicating with the lower wall of the primary pneumatic, the opposite wall having a port communicating with the vacuum chamber, a valve casing mounted upon one of said walls, and valves operatively connected with the diaphragm of the primary pneumatic.

27. In a pneumatic action for musical instruments, the combination of a vacuum chamber casing, a primary pneumatic casing positioned within the casing, having opposite walls with an interposed diaphragm, a conduit adapted for connection with the tracker bar communicating with the lower wall of the primary pneumatic, the opposite wall having a port communicating with the vacuum chamber, an air tight valve casing supported upon the ported wall of the primary pneumatic and communicating with the interior thereof, valve seats in the valve casing, and valve parts to engage said seats, a vent port for the valve casing leading to the outside of the vacuum chamber casing, and a motor pneumatic having communication with the valve casing intermediate said valve seats.

28. In a pneumatic action for musical instruments, pneumatic mechanism arranged in series within the casing, a valve casing supported on the top wall of each primary pneumatic mechanism, one of the walls of the inclosing casing having a series of openings, one for each valve casing, a motor pneumatic for each valve casing having an end to contact with said vertical wall of the inclosing casing, said motor pneumatics hav-

ing end openings communicating with the openings of the inclosing casing, and the side wall of the valve casings having openings communicating through the vacuum chamber casing with said motor pneumatics. 70

29. In a pneumatic action for musical instruments, the combination of a vacuum chamber casing, a primary pneumatic mechanism positioned within the casing and comprising a bottom wall, a top wall, an interposed diaphragm, a valve casing positioned on the top wall of the primary pneumatic mechanism and operatively connected thereto, a packing interposed between the lower end of the valve casing and the top wall of the primary pneumatic mechanism, and a motor pneumatic operatively associated with the valve casing. 75

30. In a pneumatic action for musical instruments, the combination of a vacuum chamber casing, a primary pneumatic casing positioned therein, a valve casing mounted upon the pneumatic casing, and also arranged within the vacuum chamber casing, and a removable top wall for the valve casing. 80

31. In a pneumatic action for musical instruments, the combination of a vacuum chamber casing, a vertically disposed valve casing within the vacuum chamber casing, a primary pneumatic element also within the vacuum chamber casing and connected directly to the vacuum chamber casing, and means mounted on the valve casing for engaging a side wall of the vacuum chamber casing for detachably supporting the same in place. 95

32. In a pneumatic action for musical instruments, the combination of a vacuum chamber casing, a vertically disposed valve casing within the vacuum chamber casing, a primary pneumatic element also within the vacuum chamber casing and connected directly to the vacuum chamber casing, means mounted on the valve casing for engaging a side wall of the vacuum chamber casing for detachably supporting the same in place, the opposite side wall of the vacuum chamber casing being removable whereby to permit access to the valve casing and pneumatic element. 110

33. In a pneumatic action for musical instruments, the combination of a vacuum chamber casing, a vertically disposed valve casing within the vacuum chamber casing, a primary pneumatic element also within the vacuum chamber casing and connected directly to the vacuum chamber casing, means mounted on the valve casing for engaging a side wall of the vacuum chamber casing for detachably supporting the same in place, a horizontally disposed motor pneumatic arranged without the vacuum chamber casing and having an opening in its end wall adapted to directly register with 125

an opening in said side wall of the vacuum chamber casing, and said valve casing having an opening registering with the last two mentioned openings.

5 34. In a pneumatic action for musical instruments, the combination of a vacuum chamber casing, a vertically disposed primary pneumatic mechanism within the casing, a vertically disposed valve casing 10 mounted upon the primary pneumatic mechanism, a motor pneumatic arranged without the vacuum chamber casing, and common means for detachably supporting the motor pneumatic, valve casing, and primary pneumatic upon one wall of the vacuum chamber casing.

35. In a pneumatic action for musical instruments, the combination of a vacuum chamber casing, a primary pneumatic mechanism within the casing, a valve casing 20 mounted upon the primary pneumatic mechanism, a motor pneumatic arranged without the vacuum chamber casing, common means for detachably supporting the motor pneumatic, valve casing, and primary pneumatic 25 upon one wall of the vacuum chamber casing, the opposite wall of the vacuum chamber casing being removable at will to permit application and removal of said parts.

30 36. In a device of the character described an action chest having one of its walls perforated, striker pneumatics on the exterior of the wall, valve actions mounted upon the interior of the wall and means for 35 movably securing said valve actions to the wall in operable relation to the striker pneumatics and their ducts.

37. In a device of the character described, 40 an action chest subject to air tension, a plurality of individual unit valve structures arranged therein and removable therefrom, each individual unit comprising a valve block with relief ports, a valve, a diaphragm controlling the operation of said valve and 45 suspended with reference to the valve block and open to the suction of the chest, said diaphragm having an area greater than the block but with its center coincident with the valve of said block.

50 38. In a device of the character described an action chest, striker pneumatics mounted exteriorly thereof, ducts extending through a wall of the chest and controlling the striker pneumatics, and valve actions 55 movably secured within the chest and controlling said ducts.

39. In a device of the character described, 60 the combination of an action chest, striker pneumatics, a plurality of valve members within said chest and each having an exhaust through one wall of the chest and having an open diaphragm connection with the interior of the chest, a valve arranged in

the valve chamber of each valve member, and a duct adapted to establish communication between each valve chamber and a striker pneumatic. 65

40. In a pneumatic action for musical instruments, the combination of a vacuum chamber having a back board, and a removable front board, and valve seats and diaphragms within the vacuum chamber supported upon said back board entirely independent of the front board. 70

41. In a pneumatic action for musical instruments, the combination of an action chest having a vacuum chamber with a back board, and a removable front board, and valve actions within the vacuum chamber secured to the back board and supported independently of the front board. 75

42. In a pneumatic action for musical instruments, the combination of an action chest having a vacuum chamber with a removable wall, a valve action within the 85 chamber, a striker pneumatic without the chamber, said valve action and striker pneumatic being secured at opposite sides of one wall of the chamber and independent of the removable wall thereof. 90

43. In a pneumatic action for musical instruments, the combination of a vacuum chamber having front and rear walls, a valve action within the chamber mounted upon the rear wall, an exterior motor pneumatic 95 mounted upon the rear wall, and means for mounting the front wall whereby access to the interior of the vacuum chamber and valve action may be obtained at will at the front of the casing. 100

44. An action chest having a vacuum chamber with a back board, and a removable front board, and valve seats and diaphragms within the vacuum chamber and supported entirely independently of the front board. 105

45. An action chest having a vacuum chamber with a back board, and a removable front board, and valve seats and diaphragms within the vacuum chamber secured to the back board and supported entirely independently of the front board. 110

46. In a pneumatic action for musical instruments, the combination of a diaphragm, a valve operatively connected therewith, a vacuum chamber casing, the diaphragm and valve being positioned within and inclosed by the vacuum chamber casing, and a motor pneumatic positioned without the vacuum chamber casing and mounted upon one wall thereof. 115

In testimony whereof I hereunto affix my signature in the presence of two witnesses.
